CLAIM

The ornamental design for a caning gauge, as shown and described.

DESCRIPTION

FIG. 1 is a front side view of a first embodiment of the caning gauge showing my new design, the rear side view being a mirror image and omitting the etched rectangular markings;

FIG. 2 is a top side view of a first embodiment of the caning gauge;

FIG. 3 is a bottom view of a first embodiment of the caning gauge;

FIG. 4 is right side view of a first embodiment of the caning gauge;

FIG. 5 is a left side view of a first embodiment of the caning gauge;

FIG. 6 is a front side view of a second embodiment of the caning gauge, the rear side view being a mirror image and omitting the etched rectangular markings;

FIG. 7 is a top side view of the second embodiment of the caning gauge;

FIG. 8 is a bottom side view of the second embodiment of the caning gauge;

FIG. 9 is a right side view of the second embodiment of the caning gauge; and,

FIG. 10 is a left side view of the second embodiment of the caning gauge.
